(57) **CLAIM**

We claim the ornamental design for a micrometer head, as shown and described.

DESCRIPTION

FIG. 1 is a front perspective view of one embodiment of a micrometer head.

FIG. 2 is a rear perspective view thereof.

FIG. 3 is a front view thereof.

FIG. 4 is a rear view thereof.

FIG. 5 is a left-side view thereof.

FIG. 6 is a right-side view thereof.

FIG. 7 is a top view thereof.

FIG. 8 is a bottom view thereof.

FIG. 9 is a front view of another embodiment, in which a rotatable display is rotated; and,

FIG. 10 is a front view of a still further embodiment, in which a rotatable display is rotated.

The broken lines depict environmental subject matter only and form no part of the claimed design.
